UNITED STATES PATENT OFFICE

WILLIAM J. NEELY, OF FREEPORT, ILLINOIS, ASSIGNOR TO THE W. T. RAWLEIGH COMPANY, OF FREEPORT, ILLINOIS, A CORPORATION OF ILLINOIS

TOOTHEBRUSH TRIMMING MACHINE

Application filed November 11, 1931. Serial No. 574,450.

This invention relates to brush trimming machines, and more particularly to tooth brush trimming machines.

In trimming the bristles of tooth brushes in accordance with well known practices, it is necessary to first give the bristles a rough or primary cut, and then give them a finishing or final cut. There are no commercial machines now on the market that are able to perform the necessary trimming operation by a single cut, and it is therefore necessary to place each tooth brush in two different machines, one to produce the rough cut, and the other to produce the finishing cut. This practice necessarily entails an undesirable amount of handling of the brushes by the machine operator, because he must handle each brush four times before it can be properly trimmed. That is, he must place it in the first machine, give it the rough cut, and then remove it from that machine; then he must place it in the second machine, give it the finishing cut, and then remove it therefrom.

In some cases, one machine is used to make both cuts on a brush, but the same number of handlings of each brush is necessary. An operator carefully adjusts the machine for the rough cut, and then runs a few hundred or more brushes through the machine. He then carefully changes the adjustment for the finishing cut, and runs the same brushes through the machine again. Obviously this system is of no advantage over the one in which two machines are used, because in each case the operator must handle each brush no less than four times.

The primary object of my invention is to provide a brush trimming machine in which both cutting operations can be performed during a single pass of the brush through the machine, and with a minimum number of handlings by the operator.

It is a further object of the invention to provide a machine in which a brush may be given first a rough cut, and then immediately thereafter, and without the necessity of altering delicate adjustments, the same brush may be given a finishing cut in the same machine, without the necessity of intermediate handlings thereof.

It is a further object of the invention to produce a machine in which a brush holding slide is supported in spaced relation to a rotary knife, and to provide means for changing the relation of this slide with respect to the knife during the operation of the machine, so that the slide may assume two definite positions to perform the two necessary trimming steps. 55

It is a further object of the invention to provide an independent fine adjustment between the brush holding slide and the rotary knives, in addition to the aforementioned means for causing said slide to assume two different positions during the operation of 65 the machine.

In the accompanying drawings an embodiment of the invention is shown, in which:

Figure 1 is a side elevation of the complete machine, including the supporting table and 70 foot operated treadle.

Figure 2 is a plan view of the machine, with the operating handle broken away for the sake of clearness.

Figure 3 is a vertical sectional view taken 75 on line 3—3 of Figure 2.

Like reference characters refer to like parts throughout the several views.

A supporting table is shown having a top or supporting frame-work 10 and legs 11. A shaft 12 is journaled at its ends in appropriate bearings 13 mounted on the table 1, and is connected to an electric motor or other source of power, not shown. A rotary brush trimming knife 14 of any approved construction but preferably of the spiral type, is fixed to the shaft 12 at a point approximately intermediate its length, and substantially midway between the sides of the table top. This rotary knife cooperates with a conventional 80 stationing blade 15 which is adjustably mounted for longitudinal movement on the support 16 by the adjusting screw 17. Said support 16 is pivoted to a stationary box 85 secured to the table and is vertically adjustable by a screw 18, to vary the vertical relation of the stationary blade 15 with the rotary blade 14. This arrangement of the trimming knives is well known in the art and is 90 not itself a part of my invention. 95

A brush holding slide is mounted above the rotary knife by a means which will be described below. This slide is provided with a tooth brush receiving socket 20 into which the brush 21 to be trimmed may be placed, with its bristles 22 extending through an orifice 23 in the bottom of the socket. An operating lever 24 is pivoted to the slide 19 and is provided with a foot 25 which is adapted to be pressed down on the back of the brush 21 to hold it firmly in the socket during the trimming operation. The lever is also provided with a hand grip 26 by which the operator reciprocates the slide to bring the brush over the face of the rotating knife.

The slide is mounted for reciprocation on a slide support 27 made up of side bars 28 and end members 29—30. The slide is held in place on the slide support by side pieces 31 having undercut grooves 32 at their inner edges. The slide may be reciprocated on the support against the action of a spring 33 which surrounds a rod 34 secured to the slide and projecting through a block 35 on the end member 29 of the slide support, as will be readily apparent from Figs. 2 and 3 of the drawings.

The slide support is pivotally mounted for swinging movement at one of its ends. This mounting is shown in the drawings as comprising a hinged connection between a pair of downwardly projecting ears 36 on the rear end member 29 of the slide support, and a vertically adjustable member 37 mounted at the rear of the table. The two parts comprising the hinged joint are interconnected by a rod 38. Said vertically adjustable member 37 is preferably provided with a lower cylindrical body portion 39 which is received in a socket member 40 at the rear of the table. A set screw 41 or any other appropriate locking means is provided for the purpose of securing the member 39 in the desired adjusted position.

It will be apparent to one skilled in the art that a slight adjustment of the member 37 either upwardly or downwardly in the cylinder 40 will result in a fine variation in the space between the rotary knife 14 and the brush holding slide 19 for the purpose of making delicate adjustments in the length of the bristles which are trimmed by the machine.

The other end of the slide support of the machine of my invention is connected to a supporting means which is movable between two limits to swing the slide support toward and away from the trimming knife. Means are provided for moving the supporting means to each of said limits so that said slide support may assume two different trimming positions with respect to the trimming knife. The front end 30 of the slide support is provided with a pair of downwardly extending ears 42 which are connected, by

means of a pin 43 to a head 44 secured to the upper end of a vertically reciprocable rod 45. This rod and the head thereon constitute the supporting means mentioned above. Said rod is mounted for reciprocating movement in a cylindrical bore in a guide member 46 secured to the front end of the table top 10. Between the upper surface 47 of the guide member 46 and the lower surface of the head 44, there is disposed a compression spring 48 which constantly tends to urge the rod 45 and the slide support 19 upwardly. The limit of upward movement of these parts is defined by the location of a collar 49 fixed to the shaft 45 below the guide member 46. This collar abuts the lower surface of said guide member and prevents the rod from moving upwardly beyond a predetermined point. When the parts are in this upwardly extended position, the machine is ready to perform the initial trimming operation, or the rough cut.

Means are provided for moving the supporting member 45 for the slide support 19 downwardly to a predetermined position. In the embodiment of the machine shown in my drawings this means includes a substantially horizontal lever 50 connected at one of its ends to a downwardly depending bar 51 secured to the rear of the table, and connected at its other end to the lower end of the rod 45 by a pivotal connection 52. This lever is preferably connected to a foot treadle 53 by a link 54. It will thus be seen that when force is applied to the foot treadle 53, the rod 45 will be moved to its lower limit of movement, and the slide support will be oscillated about the hinge pin 38 to move the same a substantial distance nearer to the trimming knife 14. The downward movement of the slide support 27 and the supporting means 45 therefore is limited by an adjustable abutment 55 screwed into the front of the table below an extension of the head 44. Consequently, if it is desired to vary the point to which the slide support may be moved toward the knife by the treadle 53, this can readily be accomplished by screwing the abutment bolt 55 into or out of the table the desired amount. When the parts are in this downwardly depressed position, the machine is ready to perform the second trimming operation, or the finishing cut.

In addition to the previously described means for defining the limits of movement of the movable support 45 for the slide support, which means in turn define the two trimming positions of the machine, the vertically adjustable mounting member 37 to which the other end of the slide support is hinged constitutes another means to change said two trimming positions. For instance, if the member 37 is raised a substantial amount, the slide support will be correspondingly raised with respect to the trimming knife,

and, consequently, both of the trimming positions of the machine will be changed so that a brush having longer bristles will be produced. The advantages of a delicately adjustable mounting for one end of the slide support in combination with a reciprocable support for the other end thereof will be apparent to one skilled in the art.

In the operation of my improved machine, the operator with his left hand places a tooth brush in the socket 20 in the brush holding slide 19. He then swings the operating handle downwardly so that the foot 25 engages the back of the brush and firmly positions it in the socket. He then pushes the slide upwardly over the inclined surface of the slide support while the slide support and its supporting parts are substantially in the position of Fig. 3, and the brush is given a rough cut. He then permits the spring 33 to return the slide to its initial position. He then depresses the foot treadle 53 which in turn moves the supporting means for the slide support and the slide support downwardly to their lower limit of movement. When in this position, the slide 19 and the slide support will be in the correct position to give the brush its finishing cut. While maintaining the foot treadle in its depressed position, the operator again reciprocates the slide 19 upwardly so as to bring the brush over the face of the knife 14 for the final trimming operation. The slide is then returned by the spring 33 to its original position, the foot treadle is released, and the slide support is automatically returned to its initial trimming position by the spring 48. The parts are then in position to receive another brush to be trimmed.

Because the above described operations are all very simple, an operator is able to trim an extremely large number of brushes in a given time. It will be seen that it is necessary to handle each brush only twice during the complete trimming operation. The brush is put in the machine then given two cuts by simply reciprocating the slide 19 twice and depressing the foot treadle 53 once. The completely trimmed brush is then removed. As stated above it has always been necessary with machines of the prior art to handle each brush at least four times before it could be trimmed completely.

It will be apparent from this specification when considered in connection with the accompanying drawings that I have provided a machine which accomplishes the stated objects of the invention. Certain changes in the details of construction may be resorted to without departing from my invention as defined in the accompanying claims.

I claim:—

1. A brush trimming machine comprising a rotary knife, a brush holding slide, and a slide support pivotally mounted at one end for swinging movement with respect to said

knife, a supporting means for the other end of said slide support, said means being movable to swing said slide support toward and away from said knife, resilient means urging said supporting means to one limit of its movement, and other means operable to move said supporting means to its other limit of movement, whereby said slide support may assume two different trimming positions. 70

2. A brush trimming machine comprising a rotary knife, a brush holding slide, and a slide support pivotally mounted at one end for swinging movement with respect to said knife, a supporting means for the other end of said slide support, said means being movable to swing said slide support toward and away from said knife, means adapted to cause said supporting means to move to one limit of its movement, and a lever operatively associated with said means to move it to its 80 other limit of movement, whereby said slide support may assume two different trimming positions. 85

3. A brush trimming machine comprising a supporting frame, a rotary knife on said frame, a brush holding slide, and a slide support pivotally mounted at one end to said frame for swinging movement with respect to said knife, a supporting means for the other end of said slide support, said means being 90 movable to swing said slide support toward and away from said knife, resilient means urging said supporting means to one limit of its movement, and a lever operatively associated with said means to move it to its other 95 limit of movement, whereby said slide support may assume two different trimming positions. 100

4. A brush trimming machine comprising a supporting frame, a rotary knife on said frame, a brush holding slide, and a slide support pivotally mounted at one end to said frame for swinging movement with respect to said knife, a supporting means for the other end of said slide support, said means being 105 movable to swing said slide support toward and away from said knife, means adapted to cause said supporting means to move to one limit of its movement, and a foot operated treadle operatively associated with said 110 means to move it to its other limit of movement, whereby said slide support may assume 115 two different trimming positions.

5. A brush trimming machine comprising a supporting frame, a rotary knife on said 120 frame, a brush holding slide, and a slide support pivotally mounted at one end to said frame for swinging movement with respect to said knife, said pivotal mounting being adjustable to vary the relation of said pivoted end of said slide support to said knife, a supporting means for the other end of said slide support, said means being movable between two limits to swing said slide support about said pivot toward and away from said knife, 125 130

- means adapted to cause said supporting means to move to one limit of its movement, and other means to move it to its other limit of movement, whereby said slide support may be caused to assume two different trimming positions with respect to said knife, said adjustable pivotal mounting constituting means to change said two different trimming positions.
6. A brush trimming machine comprising a supporting frame, a rotary knife on said frame, a brush holding slide and a slide support pivotally mounted at one end to said frame for swinging movement with respect to said knife, a supporting means for the other end of said slide support, said means being movable to swing said slide support toward or away from said knife to two trimming positions, means operating on said supporting means to cause said slide support to assume an initial trimming position, and other means operable on said supporting means to move said slide support to a second trimming position, said first mentioned means operating on said supporting means to return said slide support to said initial trimming position.
7. A brush trimming machine comprising a supporting frame, a rotary knife on said frame, a brush holding slide and a slide support pivotally mounted at one end to said frame for swinging movement with respect to said knife, a supporting means for the other end of said slide support, said means being movable to swing said slide support toward or away from said knife to two trimming positions, resilient means operating on said supporting means to cause said slide support to assume an initial trimming position, and other means operable on said supporting means to cause said slide support to assume a second trimming position, said resilient means operating on said supporting means to return said slide support to said initial trimming position.
8. A brush trimming machine comprising a supporting frame, a rotary knife on said frame, a brush holding slide and a slide support pivotally mounted at one end to said frame for swinging movement with respect to said knife, a supporting means for the other end of said slide support, said means being movable to swing said slide support toward or away from said knife to two trimming positions, resilient means operating on said supporting means to cause said slide support to assume an initial trimming position, and a lever operatively connected to said supporting means and being adapted upon the application of force thereto to move said slide support against the action of said resilient means to a second trimming position, said resilient means being adapted to return said slide support to said initial trimming position when said force is removed from said lever.
9. A brush trimming machine comprising a supporting frame a rotary knife on said frame, a brush holding slide, and a slide support pivotally mounted at one end to said frame for swinging movement with respect to said knife, a supporting member for the other end of said slide support, said member comprising a rod reciprocable between two limits to swing said slide support toward or away from said knife, a compression spring surrounding said rod and connected therewith to urge said rod to one of its limits of movement, a lever operatively connected with said rod and being adapted upon the application of force thereto to move said rod against the action of said compression spring to its other limit of movement, whereby said slide support may assume two different trimming positions defined by said two limits of movement of said rod.
10. A brush trimming machine comprising a supporting frame, a rotary knife on said frame, a brush holding slide, and a slide support pivotally mounted at one end to said frame for swinging movement with respect to said knife, a supporting member for the other end of said slide support, said member comprising a rod reciprocable between two limits to swing said slide support toward or away from said knife, one of said limits being defined by an adjustable abutment, a compression spring surrounding said rod and connected therewith to urge said rod to one of its limits of movement, a lever operatively connected with said rod and being adapted upon the application of force thereto to move said rod against the action of said compression spring to its other limit of movement, whereby said slide support may assume two different trimming positions defined by said two limits of movement of said rod, one of said positions being variable in accordance with the position of said adjustable abutment.
11. A brush trimming machine comprising a supporting frame, a rotary knife on said frame, a brush holding slide, and a slide support, said slide support being pivotally mounted at one end to a vertically adjustable member associated with said frame for swinging movement with respect to said knife, said vertically adjustable member being movable to provide a fine variation in the space between said slide support and said knife; and a supporting means for the other end of said slide support, said means being movable between two limits of movement to swing said slide support toward and away from said knife, and means to move said supporting means to each of said limits of movement, whereby said slide support may assume two different trimming positions corresponding to said two limits of movement.

12. A brush trimming machine comprising a table, a rotary knife mounted on said table, a brush holding slide, and a slide support pivotally mounted at one end on said table for swinging movement with respect to said knife, a supporting means for the other end of said slide support, said means being vertically reciprocable between upper and lower limits to swing said slide support to ward or away from said knife to two trimming positions corresponding respectively to said upper and lower limits, resilient means constantly urging said supporting means to said upper limit of movement, a foot treadle operatively connected to said supporting means to move the same to its lower limit of movement, said operative connections comprising a cross lever pivoted at one of its ends to said table and also attached to said reciprocable slide support, and a link between said foot treadle and said cross lever, whereby motion may be transmitted from said treadle through said link and said cross lever to said reciprocable support to move the latter to its lower limit of movement.

In testimony whereof I affix my signature.
WILLIAM J. NEELY.
